UNITED STATES PATENT OFFICE.

GEORGE W. BLAKESLEY, OF ROCK ISLAND, ILLINOIS.

DESIGN FOR A HEATING-STOVE.

SPECIFICATION forming part of Design No. 28,120, dated January 4, 1898.

Application filed September 20, 1897. Serial No. 652,384. Term of patent 3½ years.

To all whom it may concern:

Be it known that I, GEORGE W. BLAKESLEY, a citizen of the United States, residing at Rock Island, Rock Island county, Illinois, have invented and produced a new and original Design for Heating-Stoves, of which the following is a specification, reference being had to the accompanying drawings, in which—

Figure 1 is a front elevation of the stove. Fig. 2 is a side elevation of the stove. Fig. 3 is a plan view of the top of the stove with the urn removed.

The body A of the stove is elliptical in horizontal section and is encircled at bottom and top by bands of corrugations *a a*. The body rests upon a base B, supported by four legs *l*. A conspicuous feature of the front of the stove is an upper extension *b* of the base of the stove, which covers the lower part of the front of the body of the stove like an apron. The lower front of the base is extended downward into a pouch-like form closed in front by the lift-door *D*, dependent from the "apron" *b*. The lift-damper *d* consists of a plate tapering upward into a relatively long shank above and terminating between projecting lugs on the apron *b*. Encircling the hinge-lugs is a plate *e*. A metallic shield *s* extends vertically from the base to the top of the stove in the middle of the front. The top of the stove surmounting the body is convex, has a pipe-flue at the back, and an ornamental urn *m* in the center. The base, foot-rests *ff*, legs, and lift-door are ornamented with raised work of a conventionalized floral design, as shown.

The same general design appears also on the top of the stove, which consists of three well-defined portions—an outer elliptical flange with the raised ornamentation carried all the way around it, an inner band of about the same width, also ornamented, and a central elliptical cover having similar ornamentation somewhat more ornate than on the bands, its front and rear edges being scalloped and radial ridges extending from the foot of the urn corresponding to the scallops. The urn rises from the center of the top and consists of an approximately spherical body supported on a standard surmounted by a harp-shaped ornament and having on each side a small grille, as shown. The raised ornamentation is carried to all parts of the stove except the body proper, appearing in the variety of forms shown. The body is smooth except for the corrugations mentioned.

Having thus described my invention, what I claim as new, and desire to secure by Letters Patent, is—

1. The design for a stove herein described and shown.
2. In the design for a stove the design for a damper-plate, herein described and shown.
3. In the design for a stove the design for a base herein described and shown.
4. In the design for a stove the design for a top herein described and shown.

GEO. W. BLAKESLEY.
